LATCH AND LOCK MECHANISM

James P. McKinney, Jr., Pittsburgh, Pa., assignor,
by mesne assignments, to The American Hard-
ware Corporation, New Britain, Conn.

Application July 15, 1932, Serial No. 622,578

31 Claims. (Cl. 70—91)

This invention relates to latch and lock mechanism. It relates more particularly to latch and lock mechanism adapted for use in connection with doors and other closures.

5 The invention still more particularly relates to a latch or lock unit of simplified and improved construction. A handle unit is provided which is adapted for connection with a latch or lock mechanism after assembly of the latter, improved lock 10 actuating means are provided and the general construction of the unit is rendered relatively foolproof, easy to assemble and install, inexpensive to manufacture and highly efficient from the standpoint of operation.

15 The invention is in the nature of certain improvements over certain prior patents owned by my assignee, including Wread Reissue Patent No. 13,399, my own Patent No. 1,865,128 and others.

20 Other objects and advantages of the invention will become apparent as the following description of certain present preferred embodiments thereof proceeds.

25 In the accompanying drawings I have shown certain present preferred embodiments of the invention, in which

Figure 1 is a vertical cross-sectional view through a door having a lock mechanism applied thereto, taken along the line I—I of Figure 2;

30 Figure 2 is a horizontal cross-sectional view of a portion of the mechanism shown in Figure 1;

Figure 3 is a vertical cross-sectional view taken along the line III—III of Figure 1;

35 Figure 4 is a detail view of a portion of the mechanism shown in Figures 1 and 2, and with the knob removed from the spindle;

Figure 5 is a vertical cross-sectional view through a portion of the operating mechanism;

Figure 6 is a horizontal cross-sectional view taken along the line VI—VI of Figure 5;

40 Figure 7 is a vertical cross-sectional view taken along the line VII—VII of Figure 6;

Figures 8 to 13, inclusive, are detail views showing certain parts of the mechanism, Figures 10 and 11 being views of the same part taken at right angles to each other;

Figure 14 is a cross-sectional view similar to the left-hand portion of Figure 1 showing a modified construction;

Figure 15 is a cross-sectional view taken on the line XV—XV of Figure 14; and

Figure 16 is a perspective view to enlarged scale of a stud for maintaining the handle in place on the spindle.

Referring more particularly to the drawings, there is represented in Figures 1, 2 and 3 a door

2 having a through bore 3 and a lateral bore 4 communicating with the bore 3 and terminating in the edge of the door. Positioned within the bore 3 is a casing 5 having a generally cylindrical body portion 6 and ends 7 and 8. Although both ends 7 and 8 may be made removable if desired, the former is shown as formed integrally with the body portion 6 of the casing and having an outwardly extending hollow cylindrical bearing portion 9 which is externally threaded as at 10. The end piece 8 is removably connected with the body portion 6 of the casing, being fastened thereto by screws 11, and also has an outwardly extending hollow cylindrical bearing portion 12 which is externally threaded as at 13.

Rotatably mounted within the hollow cylindrical bearing portion 9 is a hollow spindle 14 having a radial enlargement 15. A washer 16 is positioned against the outer extremity of the bearing portion 9, and the radial enlargement 15 of the spindle 14 lies against the washer. The spindle is rotatable with respect to the bearing portion 9.

Fastened to the inner end of the spindle 14 by screws 17 is a plate 18 carrying a retracting cam or rollback 19. Maintained in place between the plate 18 and the inner surface of the end 7 of the casing, but rotatable independently of the plate 18 and also rotatable relatively to the casing, is a ring 20 for a purpose to be presently described.

Positioned within the hollow spindle 14 is a spindle 21 having connected with its inner extremity a plate 22 which lies against the inner face of the plate 18. The plate 22 has a laterally projecting tongue 23. The ring 20, shown in detail in Figures 10 and 11, has a radially inwardly projecting portion 24 which is adapted to lie between the plate 18 and the end 7 of the casing and by which the ring is maintained in place.

The ring also has an axially extending portion 25 which extends beyond the inner surface of the plate 18. Such portion 25 of the ring 20 is provided with a slot 26. The plate 22, except for the tongue 23, is contained within the periphery of the plate 18, but the tongue 23 extends laterally past the periphery of the plate 18 and into the slot 26 formed in the portion 25 of the ring 20.

Thus, assuming the hollow spindle 14, and consequently also the plate 18 carrying the retracting cam 19, to be stationary, the inner spindle 21 is free to rotate and the plate 22, being connected therewith, rotates with such inner spindle and causes rotation of the ring 20. As appears from Figure 7, the spindle 21, together with

with its plate 22 and the ring 20, may thus be rotated through well over half a circle without danger of the tongue 23 encountering the retracting cam 19, such rotation being amply sufficient 5 for the purpose intended. Likewise the spindle 14, plate 18 and cam 19 may be rotated through a limited arc sufficient to accomplish their function, which will presently be described, without interference with the tongue 23 of the 10 plate 22 and independently of the spindle 21 and its associated mechanism. Therefore, for operative purposes the spindle 14, plate 18 and cam 19 may be considered as one independently 15 rotatable unit, and the spindle 21, plate 22 and ring 20 may be considered as another independently rotatable unit.

Rotatably mounted within the hollow cylindrical bearing portion 12 of the end piece 8 is a spindle 27 having a pair of oppositely disposed radial projections 28. The inner surfaces of the 20 projections 28 lie against the outer extremity of the bearing portion 12. The spindle 27 is rotatable with respect to the bearing portion 12.

Fastened to the inner end of the spindle 27 by 25 screws 29 is a plate 30 carrying a retracting cam 31. Thus the spindle 27, plate 30 and cam 31 form a rotatable unit analogous to the rotatable unit formed by the spindle 14, plate 18 and cam 19 at the opposite end of the casing. The spindle 14 also has a pair of oppositely disposed radial projections 32 similar to the projections 28 on the spindle 27.

Mounted in each of the spindles 14 and 27 is 30 a stud 33 the nose of which is adapted to project beyond the outer surface of the spindle, such stud being urged outwardly by a coil spring 34, but being suitably held against complete dislodgment from the spindle.

There is provided a handle unit, designated 35 generally by reference numeral 35, adapted for attachment to cooperate with the spindles 14 and 21 after the casing and associated mechanism have been assembled and installed in the door. Such handle unit comprises an outer manually 40 operable rotatable member in the form of a knob 36 having a hollow shank 37. The end of the shank 37 is provided with opposite notches 38 adapted to receive the projections 32 and with a hole 39 adapted to receive the outwardly projecting extremity of the spring pressed stud 33. 45 When the knob 36 is pushed onto the spindle 14 the stud 33 is depressed to permit the end of the shank to pass thereover, the notches 38 engage with the projections 32 and the stud 33 springs 50 outwardly into the hole 39 under the action of the spring 34 so as to hold the knob against axial withdrawal except when the stud 33 is depressed so that its outer extremity is within the 55 confines of the spindle 14. The inter-engagement 60 of the notches 38 and the projections 32 insures rotation of the spindle 14 upon rotation of the knob 36.

Fastened within the knob 36 so as to form there- 65 with the unit 35 is a key-operated device 40 of any suitable or well known construction, such, for example, as that disclosed and claimed in the co-pending application of Marcus Holpfer, Serial No. 532,527, which is owned by my assignee. The key- 70 operated device 40 comprises a key-rotatable portion adapted to cooperate with the spindle 21 to rotate the same and having a notch 41 adapted to inter-engage with an outward projection 42 on the end of the spindle 21. Thus upon insertion 75 of the key and turning thereof the spindle 21, together with its plate 22 and the ring 20, will be

rotated for a purpose to be presently described. When the key is not inserted and the knob 36 is manually rotated, both the spindle 14 and the spindle 21 will be rotated, but the extent of rotation necessary to accomplish the function of the 5 knob is through only a small arc and not sufficient to cause the ring 20 to perform the function for which it is intended and which it performs only upon insertion of the key and turning 10 of the spindle 21 and its associated mechanism through an angle greater than the angle traversed by the spindle 14 and its associated mechanism in operation.

The opposite knob 43 is connected with the 15 spindle 27 in the same general manner as above described with respect to the knob 36, although the knob 43 may be solid or may at least have a closed outer end, having no key-operable device associated therewith. The handle unit 35 is adapted to be used at the outside of the door and 20 the knob 43 at the inside of the door. Aside from the fact that the knob of the outer handle unit contains the key-operable device, the knobs 25 may be of the same construction and dimensions.

The casing 5 has oppositely disposed openings 44 and 45 in its cylindrical surface, the latter of which has an outward notch 46. There is disposed within the casing a bolt retractor 47 having a bore therethrough the axis of which is aligned with the axis of the openings 44 and 45. 30 The retractor 47 is urged toward the right, viewing Figure 5 and 6, by a coil spring 48 which bears against the rear casing wall. The retractor 47 and spring 48 are inserted into the 35 casing from the open end thereof before application of the end piece 8. A guide member 49 is inserted through the opening 45 and through the bore of the retractor 47, its forward extremity seating within the inner portion of the opening 44 which is slightly enlarged for the purpose. The 40 guide member 49 has a forked rearward portion 50, for a purpose to be presently described, and also has a longitudinal slot 51 for a purpose also to be presently described. The slot 51 is aligned 45 with the notch 46 in the opening 45.

A bolt carrier 52 is inserted into the casing 50 through the opening 45, such bolt carrier having a lateral projection 53 which passes through the notch 46 and is positioned within the slot 51. The bolt carrier 52 is longitudinally guided within the 55 guide 49 while the retractor 47 is longitudinally guided exteriorly thereof. The projection 53 on the bolt carrier extends through the slot 51 and lies behind the retractor so that upon movement 60 of the retractor toward the left, viewing Figures 5 and 6, the retractor moves the bolt carrier with it. The forward end of the bolt carrier extends through the opening 44 and is hollowed and internally threaded for the reception of a bolt stem 65 carrying a bolt head 55. The rear portion of the bolt carrier 52 is also hollowed for the reception of the forward end of a coil spring 56, which urges the bolt carrier toward the right and which is inserted through the opening 45. After the 70 parts have been inserted and assembled as above described a cover plate 57 is inserted through the open end of the casing and into a groove provided in the interior of the casing and between the prongs of the forked end 50 of the guide 49 to 75 prevent removal of the guide and bolt carrier and to serve as a bearing for the spring 56.

Thus the bolt carrier 52 and retractor 47 are independently urged in the direction of projection of the bolt, the pressure exerted on the retractor 75

by the spring 48 being considerably greater than that exerted on the bolt carrier by the spring 56. The bolt and bolt carrier may be retracted against the action of the lighter spring 56 but 5 without moving the retractor 47 or compressing its spring 48, simply by the camming action exerted on the bolt by the jamb or strike plate when the door is pushed closed. Under these conditions it is desirable that little resistance be offered to retraction of the bolt so that the door will close and latch easily.

The retractor 47 lies between the plates 18 and 30, and the respective retracting cams 19 and 31 lie forwardly of respective outwardly projecting portions 58 and 59 of the retractor. Thus 15 upon rotation of either of the knobs 36 and 43 the corresponding retracting cam will move the retractor 47 toward the left, viewing Figures 5 and 6, and the retractor will carry with it the bolt carrier 52 by reason of the engagement between the rear portion of the retractor and the projection 53 of the bolt carrier which extends through the slot 51 in the guide 49. The resistance offered to movement of the retractor and bolt carrier upon turning of either knob will include both the resistance of the stronger spring 48 and that of the lighter spring 56. It is desirable that the resistance offered to turning of the knob be relatively great as compared to that 20 offered to retraction of the bolt alone so as to give a firm "feel" to the latch mechanism. This is particularly true with the use of lever type handles which afford a rather great mechanical advantage and which, therefore, should be rather 25 strongly resisted by the spring means associated with the latch mechanism.

A decided advantage is obtained by the guiding of the bolt carrier and retractor by independent portions of the guide 49, the bolt carrier and retractor being guided independently of each other, as this eliminates any tendency toward skewing of the bolt carrier when the handle is grasped and possibly slightly turned to push or pull the door closed. This tendency toward skewing is 40 particularly noticeable with latches provided with lever type handles which afford a relatively great mechanical advantage and which may be inadvertently slightly turned when grasped, when the bolt carrier and retractor are not independently guided as above described.

The casing 5 is provided with oppositely disposed transverse slots 60 and 61 adapted selectively for the reception of a locking slide 62. Such locking slide is inserted into either one or the other of the slots 60 and 61 before the end piece 8 is put in place, the selection of the slot being determined by whether the mechanism is to be applied to a right- or a left-hand door. The appropriate slot is selected which will insure positioning of the locking slide 62 at the top of the mechanism and manually operable from the inside of the door, as will presently be described. A spring 63 of generally T shape is provided having portions 64 which are adapted to seat within 45 openings 65 in the locking slide 62 and a portion 66 which is adapted to bear against the body of the locking slide. The spring 63 has substantially centrally thereof an outwardly projecting portion 67 which, when the locking slide is inserted into the casing, is adapted to lie within one or the other of a pair of grooves 68 and 69, a pair of such grooves being provided at each side of the casing, as shown in Figure 1. The spring 63 therefore not only insures against looseness or rattling of the locking slide, but also assists in

insuring proper positioning of the locking slide in each of its two operative positions, for a purpose now to be described.

The locking slide is provided with a threaded stem 70 adapted to project through an opening 71 in the end piece 8, and in applying the end piece 8 to the casing after insertion of the locking slide the opening 71 is positioned at the side of the casing selected for the locking slide. A manually operable push-and-pull button 72 is adapted to be 10 threaded onto the stem 70 and to be accessible from the inside of the door after the entire mechanism has been assembled in place. The locking slide is moved between its two positions by grasping and appropriately pushing or pulling the button 72.

The locking slide has an inward locking projection 73 which when the bolt is fully projected, as shown in Figure 5, lies rearwardly of the transverse plane through the outwardly extending 20 crosshead portions 74 of the retractor 47. Each crosshead portion 74 has a notch 75, as shown in Figure 1, and when the portion 67 of the spring 63 is in engagement with the notch 68 in the casing the projection 73 lies directly behind the notch 25 75 so as to permit retraction of the bolt carrier upon turning either knob. However, upon movement of the locking slide to the position in which the portion 67 of the spring lies in the notch 69 the projection 73 will lie directly behind a portion 30 of the crosshead 74, thereby preventing retraction of the retractor, as any attempt to move the retractor toward the left, viewing Figure 5, will be rendered ineffectual as the crosshead portion 35 of the retractor will simply strike the projection 73 and the retractor will not move any further toward retracted position.

The locking slide 62 also has an inclined cam follower 76, as shown in Figure 12. The ring 20 has a pair of oppositely disposed inclined cams 40 77 adapted upon rotation of the ring to selectively engage the cam follower 76 on the locking slide 62 and thereby move the locking slide parallel to the axis of its stem 70. As above explained, the ring 20 is operable by the spindle 21 which, in 45 turn, is operable by the key of the lock. Insertion and turning of the key will therefore control the position of the locking slide, as turning of the key in one direction will bring one of the cams 77 against one surface of the cam follower 76 and 50 push the locking slide to the position in which the portion 67 of the spring is in engagement with the notch 69, and turning of the key in the opposite direction will cause the other cam 77 to engage with the opposite surface of the cam follower 55 76 to move the locking slide to the position in which the portion 67 of the spring is in engagement with the notch 68.

Therefore, the locking slide may be manually operated from the inside of the door to lock or 60 unlock the door as may be desired. When the door is locked from the inside the outer knob is prevented from turning due to the fact that the projection 73 on the locking slide 62 lies behind the crosshead 74 and thus prevents retraction of 65 the crosshead and consequently prevents turning of the spindle 14. However, the locking slide may be moved to unlock position from the outside of the door by insertion of the proper key and turning of the same to rotate the ring 20 to cam 70 the locking slide to the position shown in Figure 1, which will permit retraction of the retractor upon turning of the knob.

The unit made up of the casing, the mechanism contained therein and the spindles 14, 21 75

and 27 is adapted for application to a door and may be used with handles and trim of any desired type. This is of great advantage because the unit may be completely constructed and assembled without the need of any advance information as to the finish of the handles and trim to be used therewith, and the units may be stocked and assembled on the job with whatever handles and trim are desired. It is not necessary to take 10 apart any portion of the unit in application either of the trim or of the handles or lock cylinder.

The trim comprises, in addition to the handles and their associated mechanism, an outer rosette 78, an outer trim nut 79, an inner rosette 80 and 15 an inner trim nut 81. There is also provided a clamping plate 82 having pins 83 adapted to enter suitable openings in the unit and to assist in positioning the unit with respect to the door. A clamping nut 84 is used in conjunction with 20 the clamping plate 82, as will presently be described.

In applying the mechanism to a door the unit is inserted into the bore 3, the bolt carrier being pushed back sufficiently to permit of such insertion. The bore 3 need be only very slightly larger 25 than the casing as the bolt carrier may be depressed so that it lies substantially entirely within the confines of the casing. When the bolt carrier is aligned with the bore 4 it snaps out into such bore and the bolt stem 54 is screwed into it from the outside of the bore 4, the bolt and bolt guide being connected in the usual manner. The effective length of the bolt, or the adjustment of the bolt, may be controlled by reason of the threaded 30 connection between the bolt stem and the bolt carrier and without variation of the effect of the springs which are positioned within the casing.

The clamping plate 82 is positioned against the inside of the door with its pins 83 projecting into the holes provided therefor in the casing. Likewise the outer rosette 78 is put in place over the outer spindle 14 and so that the edge of the rosette engages the outside of the door. Then the outer trim nut 79 and the clamping nut 84 are threaded up on the respective threaded extensions of the casing, pressing respectively against the outer rosette 78 and the clamping plate 82 so as to properly position and hold the casing in the door. The clamping plate 82 has an opening 85 adapted 45 to receive the stem 70 of the locking slide and also has openings 86 for the heads of the screws 11 in the event that the clamping plate lies close to the casing. The clamping plate also has tooth-like portions 87 adapted to engage the surface of 50 the door to prevent slippage between the clamping plate and the door.

After the unit has thus been properly positioned with respect to the door, the inner rosette 80 is placed over the spindle 27 and outside the clamping nut 84, and the button 72 is threaded onto the stem 70 of the locking slide 62. The outer rosette 80 has an opening 88 through which the shank 89 of the button 72 is adapted to pass, the cross section of such opening being substantially the same as the cross-section of the shank 55 of the button so that when the parts are finally assembled the button will be held against rotation with respect to the stem 70 by the inner rosette 80. During threading of the button onto 60 the stem 70 the opening 88 in the rosette 80 is maintained about the reduced portion 90 of the button, and after the button has reached its desired position the rosette is pushed up into contact with the inner surface of the door and the inner trim nut 81 is threaded within the clamping 70

nut 84, as shown in Figures 1 and 2, so as to press the inner rosette 80 against the door and maintain the same in place.

Suitable holes 91 are provided in the respective trim nuts for the reception of a capstan wrench 5 to tighten the same in place, and similar holes may also be provided in the clamping nut 84.

The entire mechanism, with the single exception of the handles and their associated mechanism, has now been installed and properly positioned in 10 the door. In the construction of a building this may be done preliminarily to the final application of the handles or knobs, and such handles or knobs may be put in place later on. This has a great advantage in that a man especially detailed 15 for the purpose may go around and apply the handles, which greatly simplifies the matching up of the keys with the lock cylinders. The lock cylinders and the outer handles may be completely assembled before they are taken around to be attached to the lock mechanism so that it is merely necessary to push on the outer handle unit and the inner handle, as above described, and the assembly is completed.

The outer trim nut 79 is of such length in the 25 direction of its axis that when moved toward the left, viewing Figure 2, as far as it will go and against the enlarged head of the knob its right hand extremity will not uncover the stud 33. Thus even though an unauthorized person not 30 having the key to the lock should unscrew the trim nut 79, he could go no further and could not gain access to the spindle 21 controlling the locking slide as he could not remove the outer handle unit. As the trim nut 79 is screwed up 35 against the outer rosette 78 as far as it will go, it is likewise impossible for an unauthorized person to move such nut toward the door to expose the stud 33. The parts are so constructed and arranged that when the mechanism is installed 40 in the door the trim nut 79 covers the stud 33 so that when the outer handle unit is finally applied it is impossible to remove such unit except by taking down the structure beginning at the inside of the door. Thus an extremely simple and 45 easily installed structure is provided which cannot be effectively tampered with from the outside of the door.

The inner trim nut 81 likewise covers the inner stud 33, but is differently constructed in that the 50 length of the inner trim nut in the axial direction is less than the distance from the stud to the enlarged portion of the knob, and therefore a person at the inside of the door can thread back the inner trim nut 81 to expose the inner stud 33 55 and can compress such stud and remove the inner knob, thus initiating the disassembly of the entire structure. The structure is disassembled in the inverse order of its assembly as above described.

In Figures 14, 15 and 16 there is shown a somewhat modified construction for connecting the handle to the spindle. Parts corresponding to like parts in Figure 1 are identified in Figures 14, 15 and 16 by the same reference numerals as those used in Figure 1 but having a prime affixed. 60 The outer trim nut 79' is provided with a pair of oppositely disposed holes 92. The shank of the knob 36' is also provided with a pair of oppositely disposed holes 93 and the spindle 14' has a pair of oppositely disposed holes 94 of substantially 65 the same size as the holes 93 in the knob shank and terminating in reduced passages 95 communicating with the bore of the spindle. There is provided a stud 96 having a milled outer surface 70 and a reduced lower extremity 98.

In this modification the spring pressed stud 33 of the construction of Figures 1 and 2 is done away with and the assembly of the handle unit with the unit connected with the door is effected as follows: The trim nut 79' is placed over the knob shank and the handle unit and trim nut are then pushed into place over the spindle 14' so that the notches 32' interengage with the projections 32'. Upon such inter-engagement the holes 93 in the knob shank will be aligned with the holes 94 in the spindle. The holes 92 in the trim nut are then aligned with the already aligned holes in the knob shank and spindle and the stud 96 is inserted through one of the holes 92 in the trim 10 nut and is driven through such hole down into one aligned set of the holes 93 and 94 to lock the handle unit and spindle together as shown in Figure 15. The stud is driven down so that its upper surface does not project from the periphery of the knob shank, thus permitting the trim nut to be screwed up onto the threaded extension 9' of the casing to press the rosette 78' against the outside of the door and complete the assembly of the mechanism with the door. When the trim 20 nut is screwed up into position, its left-hand portion covers the stud 96, as well as both holes 93 in the knob shank, whereas the holes 92 in the trim nut are hidden from view by the rosette 78'. This effects a very strong connection between the 25 handle unit and the spindle.

An unauthorized person cannot remove the thus connected handle unit from the spindle. Even though the outer trim nut 79' is turned back and its holes 92 aligned with the holes in the knob 30 shank and spindle, it will be impossible to remove the stud 96. The inner spindle 21' will be in place and will prevent the insertion of a tool through the side of the assembly opposite the stud so as to drive the stud back out in the direction from 35 which it entered. However, when the mechanism is disassembled, beginning at the inside of the door, the inner spindle 21' may be removed and a suitable tool inserted through the holes in the trim nut, knob shank and spindle to drive the stud 40 96 out in the direction from which it entered.

When the construction just described is used it is not essential that the length of the trim nut be great enough so as to prevent retraction thereof toward the left, viewing Figure 14, so as to uncover the head of the stud at the right-hand extremity of the trim nut, as even though this could be done it would still be very difficult, if not impossible, to remove the stud. However, it is preferred to make the trim nut of such a length that it cannot be retracted toward the left, viewing Figure 14 to 50 uncover the head of the stud at the right-hand extremity of the trim nut as this renders the stud even more inaccessible and prevents the possibility that it might be removed by prying it out with a sharp tool. When the elongated trim nut is used it is practically impossible to get a purchase on the stud through one of the holes 92 in the trim nut so as to dislodge the stud. The outer milled surface of the stud cuts slightly into the walls of the holes 93 and 94 so as to positively 55 and firmly maintain the stud in place and lock the parts together. The millings are preferably inclined at a slight angle to the axis of the stud, as shown in Figure 16, so as to cause the stud to turn slightly as it is driven in, thus still more firmly effecting the connection desired.

The structure is not only easy to install, but the parts are of relatively simple construction and may be readily and quickly assembled and may be manufactured at low cost. The construction 75

is strong and rugged and ideally suited for a wide variety of applications.

The word "latch" is used in the claims as a word of broad definition and not of limitation and, unless the context of any claim prohibits, is intended to comprehend a lock in addition to what is commonly known as a latch.

While I have shown and described certain present preferred embodiments of the invention, it is to be distinctly understood that the same is not limited thereto, but may be otherwise variously embodied within the scope of the following claims.

I claim:

1. Handle structure, comprising a handle member having a shank and an enlarged outer portion and also having an opening in the shank for the reception of connecting means to connect the handle member to a latch mechanism upon application of the same thereto, a trim member adapted to cover said opening to prevent access to the connecting means, said trim member being of such length as not to uncover said opening when positioned against the enlarged outer portion of the handle member, and connecting means cooperable with said opening and operable to connect the handle member to the latch mechanism within the trim member when said trim member is in place.

2. Latch structure, comprising an assembly including spindle means adapted for preliminary application to a door in fixed relationship thereto, handle means attachable at each side of the door to said assembly after application of the latter, means for maintaining said handle means in place, and means normally covering said first mentioned means at the outside of the door and being immovable to a position uncovering said first mentioned means except upon manipulation from the inside of the door.

3. Lock structure, comprising a bolt, a retractor therefor, manually operable means for operating the retractor, means for holding the retractor against movement in one direction, means at the periphery of a portion of said manually operable means for operating said holding means, and key operable means for operating said last mentioned means.

4. Lock structure, comprising a bolt, a retractor therefor, means for operating the retractor, means for holding the retractor against movement in one direction, a cam ring disposed about a portion of said operating means and adapted to operate said holding means, and means for operating said cam ring.

5. Latch structure, comprising a casing having front and rear openings, a bolt carrier and a guide therefor both insertable into the casing through the rear opening, the bolt carrier being projectable in operation through the front opening, and means for maintaining the guide in place in the casing.

6. Latch structure, comprising a casing, a guide therein, a bolt carrier guided by one surface of said guide, and a retractor for the bolt carrier guided by another surface of said guide.

7. Latch structure, comprising a casing, a guide therein, a bolt carrier mounted generally within the guide, and a retractor for the bolt carrier mounted generally externally of the guide.

8. Latch structure comprising a casing, a hollow guide therein, a bolt carrier mounted generally within the guide, a retractor for the bolt carrier carried generally externally by the guide, and means connecting the bolt carrier and guide.

9. Latch structure, comprising a casing, a guide

- in the casing having an opening therethrough, a bolt carrier guided by one surface of said guide, a retractor for the bolt carrier guided by another surface of said guide, and means extending through said opening connecting the bolt carrier and retractor.
10. Latch structure, comprising a casing a hollow guide in the casing, a bolt carrier and a spring therefor mounted within the guide, and 10 a retractor for the bolt carrier and a spring therefor mounted externally of the guide.
11. Lock structure, comprising a bolt, a retractor therefor, spindle means for retracting said retractor, means for holding the retractor 15 against movement in one direction, means including spindle means for positively moving said holding means in both directions, and an operating unit connectible to both said spindle means and having operating portions respectively cooperable 20 with said respective spindle means.
12. Latch structure, comprising a casing having an end opening and a side opening, operating mechanism insertable into said casing through said side opening, other operating mechanism insertable into said casing through said end opening so as to cooperate with said first mentioned 25 operating mechanism, and means for closing said openings.
13. Latch structure, comprising a casing having an end opening and a side opening, a bolt retractor insertable into said casing through said side opening, a bolt carrier insertable into said casing through said end opening and so as to cooperate with said bolt retractor to be retracted 30 thereby, and means for guiding said bolt retractor and bolt carrier.
14. Lock structure, comprising a bolt, rotary retracting means for retracting the bolt, stop means for preventing retraction of the bolt by 35 said retracting means, and rotary operating means coaxial with the retracting means for operating the stop means, said operating means having a portion disposed radially outwardly with respect to said retracting means for cooperation 40 with the stop means.
15. Lock structure, comprising a bolt, rotary retracting means for retracting the bolt, stop means for preventing retraction of the bolt by said retracting means, and cam means disposed 45 at the periphery of the rotary retracting means for operating the stop means.
16. Lock structure, comprising a bolt, retracting means for retracting the bolt, stop means for preventing retraction of the bolt by said retracting means, key operable rotary means, and a separate member comprising cam means loosely connectible with said key operable rotary means upon assembly of the lock structure for operating 50 the stop means.
17. Lock structure, comprising a bolt, rotary retracting means for retracting the bolt, stop means for preventing retraction of the bolt by said retracting means, and rotary operating means for operating the stop means, said rotary operating means comprising a cam ring loosely 55 mounted about the periphery of the rotary retracting means.
18. Lock structure, comprising a bolt, a rotary plate having a rollback thereon for retracting the bolt, stop means for preventing retraction of the bolt by said rollback, and means including a second rotary plate lying against the first and rotatable relatively thereto for operating the stop means.
19. Lock structure, comprising a bolt, a rotary plate having a rollback thereon for retracting the 60 bolt, stop means for preventing retraction of the bolt by said rollback, and means including a second rotary plate lying against the first and rotatable relatively thereto for operating the stop means.
20. Lock structure, comprising a bolt, rotary means having a rollback thereon and a central opening therethrough for retracting the bolt, stop means for preventing retraction of the bolt by 65 said rollback, and means including a spindle passing through said opening in said rotary means and operating means actuated by said spindle for operating said stop means.
21. Lock structure, comprising a bolt, oppositely disposed independently operable spindles each provided with a rollback for retracting the bolt, stop means for preventing retraction of the bolt by one of said rollbacks, and rotary means 70 coaxial with one of said spindles for operating 20 said stop means.
22. Lock structure, comprising a bolt, oppositely disposed independently operable axially spaced spindles each provided with a rollback for re- 75 tracting the bolt, stop means for preventing retraction of the bolt by one of said rollbacks, and means having a portion disposed at the inner end of one of said spindles for operating said stop means.
23. Lock structure, comprising a bolt, oppositely disposed independently operable axially spaced spindles each provided with a rollback for re- 80 tracting the bolt, stop means for preventing retraction of the bolt by one of said rollbacks, another spindle coaxial with one of said first mentioned spindles, and means actuated by said last mentioned spindle and disposed at the inner end of that one of said first mentioned spindles with which the last mentioned spindle is coaxial for 85 operating said stop means.
24. Lock structure, comprising a bolt, oppositely disposed independently operable axially spaced spindles each provided with a rollback for re- 90 tracting the bolt, stop means for preventing retraction of the bolt by one of said rollbacks, and means including a rotary plate disposed across the inner end of one of said spindles and connections between said rotary plate and said stop means for operating said stop means.
25. Lock structure, comprising a bolt, oppositely disposed independently operable axially spaced spindles each provided with a rollback for re- 95 tracting the bolt, stop means for preventing retraction of the bolt by one of said rollbacks, and means including a rotary cam held in place by 55 one of said rollbacks for operating said stop means.
26. Lock structure, comprising a bolt, oppositely disposed independently operable axially spaced spindles each provided with a rollback for re- 100 tracting the bolt, stop means for preventing retraction of the bolt by one of said rollbacks, and means including a rotary cam ring surrounding one of said rollbacks for operating said stop means.
27. Lock structure, comprising a bolt, oppositely disposed independently operable axially spaced spindles each provided with a rollback for re- 105 tracting the bolt, stop means for preventing retraction of the bolt by one of said rollbacks, and means including a rotary cam ring disposed at the inner end of one of said spindles and held in place by and having a portion at the periphery of the rollback associated with said spindle for 70 operating said stop means.

28. Lock structure, comprising a bolt, a retractor therefor, first rotary means for moving said retractor to retract the bolt, means for holding the retractor against movement in one direction, 5 second rotary means for operating said holding means, said second rotary means being disposed at the periphery of said first rotary means and rotating therewith upon rotation thereof, said second rotary means being so constructed and 10 arranged as to be inoperative with respect to said holding means upon rotation of said first rotary means to retract the bolt.

29. Latch structure, comprising a casing, a tubular guide therein, a bolt carrier slidable with- 15 in said guide, a retractor mounted about said guide, a connection between the bolt carrier and retractor whereby the retractor operates the bolt carrier, and a locking slide movable into position to prevent retraction of the retractor.

30. Lock structure, comprising a bolt, retracting means therefor, stop means having limited movement in each direction for preventing retraction of the bolt by said retracting means, and cam means for operating the stop means, 5 said stop means and cam means being so constructed and arranged that movement of the cam means is limited upon movement of the stop means to its limit of movement in either direc- 10 tion.

31. Latch structure, comprising a casing having an opening, a bolt carrier and a guide therefor insertable into the casing through said opening, a spring for biasing said bolt carrier, and relatively movable means cooperating with the guide and 15 spring to hold the same within the casing.

JAMES P. MCKINNEY, JR.
